ELECTRICAL PRECIPITATOR

Walter E. Keist, Pittsburgh, Pa., assignor to The Dualtron Company, Pittsburgh, Pa., a partnership

Application July 7, 1950, Serial No. 172,517

3 Claims. (Cl. 183—7)

1

This invention relates to electrical precipitators, and more particularly to the arrangement of the different elements therein.

Electrical precipitators for removing dust from air passing through them are used both alone and in combination with heating units. It is desirable to make the precipitators as small and compact as possible, especially when they are to be used with domestic furnaces in locations where space may be rather restricted. Heretofore, precipitators have required considerable floor space because the air blowers that circulate air through them have been located at the sides of the units.

It is among the objects of this invention to provide an electrical precipitator which is very compact and in which an air blower can be mounted directly below the rest of the unit.

In accordance with this invention, an upright cabinet has an air inlet in its top and an air outlet in its bottom in a side wall. Preferably, the cabinet is rectangular with parallel side walls, and is substantially no larger in horizontal section than is necessary for accommodating the electrical precipitation unit which is mounted in the upper part of the cabinet and includes the usual dust collector plates. For washing precipitated dust from the plates, a water sprayer is disposed above them. The wash water leaving the plates is caught in a drain pan directly below the plates. This pan has an inclined lower wall extending across it, with a drain pipe connected to the lowest part of the pan. The inclined wall is provided with air passages through it, but the wash water is prevented from going through the passages by means of overlapping water deflecting members above them. The water flows down over these deflecting members to the drain pipe. Because the air passages can be located in the bottom of the drain pan, an air blower can be mounted beneath the pan instead of at one side of it, which would require a much larger cabinet or a projecting housing for the blower. An upwardly tapered space is formed between the inclined wall of the drain pan and the side of the cabinet which is adjacent the upper end of that wall. The air blower preferably projects a material distance up into the tapered space so that locating the blower in the bottom of the cabinet will not increase the height of the cabinet an objectionable amount. The blower draws air into the inlet at the top 50 of the cabinet and delivers it to the outlet near the bottom. An electric motor is mounted in the bottom of the cabinet beneath the lowest part of the drain for driving the blower. It is desirable to mount an air filter against the lower side 55 of the perforated wall of the drain pan to catch

2

any large particles of dirt that may not be deposited on the collector plates and also to collect any moisture that may splash out the pan.

5 The preferred embodiment of the invention is illustrated in the accompanying drawings, in which Fig. 1 is a side view of the precipitator with the front wall or cover removed to show the inside of the cabinet; Fig. 2 is a view of the air outlet side of the cabinet with part of the side wall broken away; and Fig. 3 is a horizontal section taken on the line III—III of Fig. 1.

10 Referring to the drawings, an upright rectangular cabinet 1 has an air inlet 2 in its top and an air outlet 3 in one side near its bottom. Directly beneath the top of the cabinet and near its front is the usual control panel 4 of an electrostatic precipitator unit. Behind the control panel are spray pipes 6 that are connected 15 through a suitable valve (not shown) to a supply pipe 7 that leads from the city water supply. Below the water sprayer is the usual ionizer 8, and below this there is a series of vertically disposed collector plates 9 on which the electrically charged dust particles are deposited as the air carries them downward between the plates.

15 After the precipitator has been operating for awhile it becomes necessary to wash the precipitated dust from the ionizer and collector plates. 20 This is done by means of the water sprayer above them. In order to collect the dirty water flowing off the lower edges of the plates, a drain pan 11 is mounted in the cabinet directly beneath the plates. A pair of opposite upper edges of this 25 pan may have lateral flanges 12 which are supported by ledges 13 attached to the inside of the cabinet, so that the pan can be slipped in and out of the cabinet by sliding the flanges on the ledges.

30 It is a feature of this invention that the major portion of the lower wall of the drain pan is inclined rather steeply downward from the side of the cabinet that contains air outlet 3. The lower end of the inclined wall terminates at a point spaced a short distance from the opposite side of the drain pan. Between that side and the lower end of the inclined wall the drain pan extends downward a short distance to form a sump 14, from the bottom of which a drain pipe 15 extends out through the adjacent side of the cabinet. With sufficient inclination, the inclined wall can be provided with openings for passage of air therethrough without any danger of the water in the pan flowing through such openings. The advantages of this are two fold. By placing 35 the air openings in the lower wall of the pan instead of in a side wall, the air blower 17 can

be located below the drain pan instead of at the side of it. Therefore, the cabinet need be substantially no larger in horizontal section than necessary to accommodate the drain pan. On the other hand, if the blower were located below the pan but the air passages were in a side wall of the pan, the cabinet would have to be materially larger than the pan to provide enough space between the pan and cabinet for an adequate flow of air down to the blower. The other advantage of inclining the lower wall of the drain pan materially is that it leaves an upwardly tapered or triangular space between that wall and the side of the cabinet facing it. A considerable portion of this space can be occupied by the blower, so the cabinet does not have to be made as tall as would be the case if the blower were completely below the lowest point of the pan. Preferably, the lower wall of the pan is inclined at an angle of about 45 degrees.

The inclined lower wall of the drain pan is conveniently formed from a rectangular frame 18 made of angle bars, across which louvers extend. Each louver is a metal strip 19 that has a slightly inclined body with a down-turned flange at its lower edge and an upwardly inclined flange along its upper edge, as shown in Fig. 2. The upper flange lies flat against the upper surfaces of the opposite sides of the frame and is attached to them. The ends of the strip engage the upright flanges of the frame and may be attached to them if desired. The strips are so arranged that they overlap one another in vertically spaced relation so that water flowing over the lower edge of each strip will fall on the strip below it. In this way the strips or louvers form waterfalls down the inclined wall to the sump 14. The spaces or slots 20 between the louvers form passages for air being drawn down through the cabinet by the blower, which is connected with air outlet 2.

The collector plates are washed only when the blower is not operating, so there is no danger of the blower sucking the wash water through the drain pan slots between the louvers. However, a little water may splash through the slots. To prevent such water from reaching the blower, a dry filter 22, such as a spun glass filter commonly used in air conditioning units, is held against the lower side of frame 18 by means of parallel flanges 23 attached to the frame. This filter collects any drops of water that pass through the slots, and the air subsequently passing through the filter soon evaporates the moisture. The filter also serves to stop any large particles of dust that are not deposited upon the collector plates.

The space below the drain pan sump is adequate for receiving an electric motor 24 that drives the blower by means of a belt 25.

According to the provisions of the patent statutes, I have explained the principle of my invention and have illustrated and described what I now consider to represent its best embodiment. However, I desire to have it understood that, within the scope of the appended claims, the invention may be practiced otherwise than as specifically illustrated and described.

I claim:

1. An electrical precipitator comprising an upright cabinet rectangular in horizontal section with parallel sides, the cabinet having an air inlet at its top and an air outlet near its bottom, an electrical precipitation unit mounted in the upper part of the cabinet and including dust collector plates having a vertical air passage between them, a water sprayer disposed above said plates

for washing precipitated dust from them when desired, a drain pan in the cabinet below the plates for receiving wash water therefrom and having an inclined lower wall extending across it to form an upwardly tapered space between that wall and the side of the cabinet that is adjacent the upper end of the inclined wall, a drain pipe connected to the pan at the lower end of said wall, the inclined wall being provided with air passages therethrough between overlapping water deflecting members that conduct the wash water to the drain pipe, and an air blower mounted entirely within the cabinet beneath the inclined wall of the drain pan and with a material portion of the blower disposed in said tapered space, the blower being adapted to draw air into said inlet and deliver it to said outlet.

2. An electrical precipitator comprising an upright cabinet rectangular in horizontal section with parallel sides, the cabinet having an air inlet at its top and an air outlet near its bottom, an electrical precipitation unit mounted in the upper part of the cabinet and including dust collector plates having a vertical air passage between them, a water sprayer disposed above said plates for washing precipitated dust from them when desired, a drain pan in the cabinet below the plates for receiving wash water therefrom and having a lower wall inclined downwardly across it from one side to a sump at the bottom of the opposite side, a drain pipe connected to the sump, the inclined wall being provided with air passages therethrough between overlapping water deflecting members that conduct the wash water to the sump, an air blower mounted in the cabinet beneath the inclined wall of the drain pan and adapted to draw air into said inlet and deliver it to said outlet, the blower extending up beside said sump and into the space between said inclined wall and the side of the cabinet, a motor beneath the sump, and means entirely within the cabinet operatively connecting the motor with the blower.

3. An electrical precipitator comprising an upright cabinet rectangular in horizontal section with parallel sides, the cabinet having an air inlet at its top and an air outlet near its bottom, an electrical precipitation unit mounted in the upper part of the cabinet and including dust collector plates having a vertical air passage between them, a water sprayer disposed above said plates for washing precipitated dust from them when desired, a drain pan in the cabinet below the plates for receiving wash water therefrom and having an inclined lower wall extending across it, a drain pipe connected to the pan at the lower end of said wall, the inclined wall being provided with air passages therethrough between overlapping water deflecting members that conduct the wash water to the drain pipe, an air filter mounted against the lower side of said inclined wall, and an air blower mounted entirely within the cabinet beneath the inclined wall of the drain pan and adapted to draw air into said inlet and deliver it to said outlet.
